UNITED STATES PATENT OFFICE.

FREDERICK MANKEY, OF WILLIAMSPORT, PENNSYLVANIA.

DESIGN FOR A CORNICE.

SPECIFICATION forming part of Design No. 16,358, dated October 27, 1885.

Application filed July 18, 1885. Serial No. 172,008. Term of patent 7 years.

To all whom it may concern:

Be it known that I, FREDERICK MANKEY, of Williamsport, Lycoming county, Pennsylvania, have invented and produced a new and original Design for Cornices, of which the following is a specification, reference being had to the accompanying photograph, forming part hereof.

Figure 1 is a front view. Fig. 2 is a transverse section.

Similar letters of reference indicate like parts.

My design is intended for ornamental cornices; and it consists, (beginning at the upper portion,) first, of a strip, A, beveled or inclined substantially as shown, or of any desired configuration. Below this is a band, B, on which is formed pyramidal elevations C and D, the elevations D being more elongated than the elevations C, and the two forms

of elevations alternating in a row. Beneath the band B is another strip, E. Beneath the strip E is an inclined band, F, on which is a row of prismatic elevations, G, formed transversely said band. Finally, beneath the band F is an inclined band, I, on which is formed a row of rectangular pyramidal elevations, J. The configuration of the strips A and E is not material to my design, and may be varied.

I claim—

The design for a cornice, substantially as herein shown and described, consisting in the strip A, band B, having pyramidal elevations C D, strip E, band F, having elevations G, and band I, having elevations J.

FREDERICK MANKEY.
